Des. 227,793
Patented July 17, 1973

227,793

GAME BOARD

Eric H. Eck, 8630 Alper Blvd., Westland, Mich. 48184

Filed Apr. 25, 1972, Ser. No. 247,502

Term of patent 14 years

Int. Cl. D21—01

U.S. Cl. D34—5 SS

In the drawing there is shown a plan view of a game board incorporating the novel design; the board is of conventional thickness and the rear view is conventionally plain.

I claim:

The ornamental design for a game board, as shown and described.
